UNITED STATES PATENT OFFICE

GLENN E. McFADDEN, OF DETROIT, MICHIGAN, ASSIGNOR TO LINCOLN MANUFACTURING COMPANY, OF DETROIT, MICHIGAN, A CORPORATION OF MICHIGAN

DESIGN FOR A CHANDELIER OR ANALOGOUS LIGHTING FIXTURE

Application filed November 18, 1929. Serial No. 33,493. Term of patent 7 years.

To all whom it may concern:

Be it known that I, GLENN E. McFADDEN, a citizen of the United States, residing at Detroit, county of Wayne, State of Michigan, have invented a new, original, and ornamental Design for a Chandelier or Analogous Lighting Fixture, of which the following is a specification, reference being had to the accompanying drawing, forming part thereof.

Fig. 1 is a front elevation.

Fig. 2 is a plan looking upwardly wherein

the decoration appears in solid line over only a portion of the same, it being understood that such decoration is repeated over corresponding parts shown only in dotted outline as shown and described.

I claim:

The ornamental design for a chandelier or analogous lighting fixture as shown and described.

GLENN E. McFADDEN.
